PUMP

Alois P. Bruce, Delavan, Wis.

Application May 6, 1948, Serial No. 25,380

3 Claims. (Cl. 103—87)

1

This invention relates to improvements in pumps, and in particular to centrifugal pumps of the type commonly used for household water systems of either the deep well or shallow well type.

Conventional centrifugal pumps employ two general types of shaft seals, namely stuffing boxes and rotary seals. The stuffing box type of seal has been unsatisfactory not only because it is expensive, but also because it requires periodic adjustment. Conventional rotary shaft seals employ a rotating carbon ring sealingly mounted on the shaft. This carbon ring is urged axially by a spring against the polished surface of a stationary metallic ring of brass or similar material which is mounted in the pump casing coaxially with the shaft.

In conventional electric motor driven centrifugal pumps the motor and the pump housings are connected by means of an adapter to which both are bolted. The conventional adapter is a unitary member, usually of cast iron, comprising an annular flange to which the motor housing is bolted spaced from a circular plate which is parallel thereto and which serves as the cover plate for the pump. Where a packing gland seal is used, an adapter with substantial spacing between the motor housing flange and circular plate is necessary to provide access for the adjustment of the packing nut.

It has been common practice to use on the rotary seal type of pumps an adapter which is approximately the same size as that used on the packing gland pumps. In the adapter heretofore used with rotary seal pumps, the plate forming the cover for the pump is formed with an outwardly projecting dome shaped portion surrounding the rotating shaft, the shaft seal being mounted in this projecting portion of the adapter. This dome shaped portion required that the motor to be spaced away from the pump housing substantially the same distance as was required by the use of a packing gland, and therefore necessitated a relatively large and expensive adapter. In addition, when the adapter having the dome shaped plate was used on a vertical pump, this dome portion had to be provided with a vent valve to release air which would otherwise be trapped thereunder upon priming of the pump. If the vent valve were not provided on this type of adapter, the rotary seal would burn out after a short running time because of lack of lubricating and cooling water.

When centrifugal pumps are used for deep well purposes, a jet eductor is used in conjunction

2

therewith in order to raise the water from the lower levels. When an eductor is used, a pressure regulating valve must be provided in the discharge of the pump. Conventional pressure regulators are expensive and complicated devices which are provided with externally accessible, adjustable means for varying the pressure which is to be maintained by the regulating valve. Such pressure regulating valves are set for the proper pressure at the factory and, though they are adjustable, they rarely, if ever, require adjustment after leaving the factory.

It is therefore a general object of the invention to provide a centrifugal pump having a rotary shaft seal which is operative equally well in either horizontal or vertical position and which requires no vent valve adjacent said shaft seal to provide for proper priming thereof.

A further object of the invention is to provide an electrically driven centrifugal pump which does not require an adapter for mounting the electric motor thereon.

A further object of the invention is to provide an improved centrifugal pump wherein a rotary shaft seal coacts directly with the housing cover plate thereof.

A further object of the invention is to provide an electrically driven pump of the class described which, by reason of the absence of an adapter, is a very compact unit.

A further object of the invention is to provide a centrifugal pump which may be adapted for deep well purposes by associating therewith a novel pressure regulating valve having very few component parts.

A more specific object of the invention is to provide a pump having an adjustable pressure regulating valve wherein access to an internal adjustment member may be quickly and easily obtained by removal of a screw plug therefrom.

Further objects of the invention are to provide a pump of the class described which is strong and durable, which may be quickly assembled and disassembled, which is inexpensive to manufacture and repair, and which is otherwise well adapted for the purposes described.

With the above and other objects in view, the invention consists of an improved pump, and all its parts and combinations as set forth in the claims, and all equivalents thereof.

In the drawing accompanying and forming a part of this application, wherein is shown one complete embodiment of the preferred form of the invention, and wherein the same reference

numerals indicate the same parts in all of the views:

Fig. 1 is a fragmentary side view of an improved electrically driven pump equipped with the improved pressure regulating valve, parts being broken away and shown in section; and

Fig. 2 is an enlarged fragmentary vertical sectional view of a portion of the interior of a modified form of the improved pump.

Referring more particularly to the drawing, the numeral 5 indicates the improved pump and the number 6 indicates the improved pressure regulating valve associated therewith. Numeral 7 indicates an electric motor for driving the pump 5.

The pump 5 shown is of the type conventionally known as a centrifugal pump and comprises a housing 8 having a centrally located inlet 9, which is threaded to receive an inlet conduit 10, and having a pair of outlets 11 and 12. The housing 5 is commonly called a volute, and is provided in its upper surface with a central chamber 19 in which an impeller 14 is rotatably mounted. The inlet 9 communicates with the chamber 19, as shown in Fig. 1. The impeller 14 is threadedly mounted on the shaft 15 of the motor 7 and rotates therewith in the chamber 19. The impeller 14 is formed with a preferably flat upper surface, a central inlet 16 and with channels 17 which extend from the inlet 16 to the periphery 18 thereof. The portion of the side wall of the chamber 19 adjacent the periphery of the impeller 14 is formed in the conventional manner with a spiral recess which communicates in the usual way with a discharge chamber 20 of the housing 8. A cylindrical recess 13 having a diameter larger than the diameter of the impeller 14 communicates with the chamber 19 and extends to the upper end of the volute 8.

A substantially flat cover plate 21 is adapted to fit the volute 8 thereby enclosing chamber 19 and recess 13. The cover plate 21 is provided with a central aperture 22 to permit passage therethrough of the motor shaft 15. A suitable gasket 23 is interposed between the plate 21 and the housing 8 to prevent leakage. The plate 21 is preferably of brass or other suitable material such as rust resistant bearing material and is preferably provided with a smoothly finished annular area on the under surface thereof surrounding the aperture 22. The upper surface of the impeller 14 is preferably provided with a centrally disposed circular recess 24 surrounding the lower portions of the shaft. The flat upper surface of the impeller is preferably spaced from the plate 21 a distance substantially less than one-half the radius of the impeller, as shown in the drawing.

Mounted on the shaft 15 between the plate 21 and the base of the recess 24 is a rotary shaft seal assembly 25. Fig. 2 shows on an enlarged scale a shaft seal assembly 25' which is in all respects identical to the assembly 25. The parts of the assembly 25' are indicated by primed reference numbers corresponding to those of the same parts of the assembly 25. The assembly 25 is comprised of a carbon ring 26 which slidably and rotatably engages the smoothly finished annular area of the plate 21 surrounding the aperture 22. The carbon ring 26 has a smoothly finished upper surface or seal face which coacts with the smooth annular surface of the plate 21 to prevent leakage therebetween. The carbon ring 26 is preferably backed with a flanged friction

sleeve 27 of rubber or other suitable resilient material which closely fits the shaft 15 in a manner to prevent any leakage along the shaft between the shaft and the sleeve 27.

5 A metallic ring 28 having an inwardly flanged lower end preferably surrounds and engages the ring 26 and the flanged portion of the sleeve 27 in any suitable manner to prevent rotation of the ring 26 relative to the sleeve 28. A second metallic ring 52 preferably surrounds the unflanged portion of the sleeve 28. The upper end of a preferably helical spring 29 engages the flange of the ring 26, and the lower end of the spring 29 is seated in the recess 24 of the impeller 14. The spring 29, acting through the sleeves 28 and 27, urges the ring 26 into engagement with the plate 21 with sufficient pressure to maintain a watertight seal therebetween at all times.

10 A modified form of the pump 5 is shown in Fig. 2 wherein the impeller 14 thereof is not provided with a central recess in its upper surface adjacent the motor shaft 15'. Fig. 2 also shows alternative construction wherein the plate 21' may be made of an inexpensive metal such as steel. The plate 21' is provided with an insert 30, of brass or other suitable material such as rust resistant bearing material, mounted in a recess 31 formed in its under-surface concentric with the aperture 22'. The insert 30 is preferably sealed in the recess 31 in any suitable manner to prevent leakage between the insert 30 and the plate 21'. The lower surface of the insert 30 is preferably smoothly finished. The rotary seal assembly 25' is identical with the rotary seal assembly 25 of Fig. 1, 15 and it coacts with the smooth surface of the insert 30 in the same manner as the rotary seal 25 coacts with the smooth annular surface portion of the plate 21 of the preferred form.

20 When the pump 5 is used for shallow well purposes, the discharge outlet 11 is usually plugged and the discharge 12 is connected with the water distribution system. However, when the pump 5 is used for deep well purposes, a conduit 32 is threadedly connected to the discharge opening 11 and leads downwardly to a jet (not shown) mounted in the lower end of the inlet conduit 10. A nipple 33 threadedly connects the discharge outlet 12 with the pressure regulating valve 6.

25 The valve 6 is comprised of a substantially tubular body 34 which is provided with a tubular extension 35 projecting at an angle therefrom as shown in Fig. 1. The body 34 is formed with a portion of reduced internal diameter as at 36 to provide a shoulder forming an annular valve seat 37. Mounted axially within the body 34 adjacent the portion of reduced diameter 36, as by the webs 38, is a hub 39. The outer end face 40 of the hub is formed with an axial bore 41 in which is threadedly mounted an axially extending adjustment screw 42. The outer surface 40 of the hub 39 and the annular valve seat 37 extend in substantially the same plane.

30 A valve member 43 of rubber or other suitable material, and having the shape of a centrally apertured disc, is mounted on the screw 42 in a manner to cooperate with the surface 40 of the hub 39 and the annular seat 37. When the valve member 43 is seated on the surfaces 37 and 40, as shown in Fig. 1, no fluid will pass through the valve. A metallic backing disc 44 having a central aperture and having a peripheral flange is preferably positioned against the outer surface of the valve member 43, as shown in Fig. 1, and a tapered helical spring 45 is pref-

erably interposed between the head of the screw 42 and the backing disc 44 in a manner to urge the valve member 43 axially against the seats 37 and 40. It is apparent that the pressure exerted on the valve member 43 by the spring 45 may be varied by turning the adjusting screw 42 either inwardly or outwardly.

The outer end of the body 34 is suitably threaded as at 46 to receive a removable plug 47. Inwardly of the threading 46 the body 34 is formed with an annular groove 48 to receive an annular gasket 49. Inwardly adjacent the groove 48 the body 34 is formed with a portion of reduced internal diameter to form a shoulder 50. It is apparent that the portion of the gasket 48 interposed between the peripheral portions of the inner surface of the plug 47 and the shoulder 50 prevents any leakage between said plug and said shoulder. A conduit 51 is threaded into the tubular extension 35 and may be connected with the conventional water distribution system.

The adjustment screw 42 is set at the factory to provide for the exertion of the proper amount of force on the valve member 43 by the spring 45. Under ordinary conditions, this setting need never be changed. If, however, it is found necessary to vary the setting of the adjustment screw 42, it is necessary only to remove the plug 47 from the body 34 by unscrewing the same. This provides ready access to the adjustment screw 42 which may be turned with a screw driver. Upon replacement of the plug 47 the valve 6 is again ready for operation.

Operation

In operation, the spring 45 will maintain the valve member 43 seated against the surfaces 37 and 40 until a predetermined pressure has been built up in the discharge chamber 20 of the pump 5. When the pressure in the discharge chamber 20 rises above this predetermined amount, it will force the valve member 43 axially outwardly along the stem of the adjustment screw 42. In so doing, the pressure in the chamber 20 overcomes the force exerted on the valve member 43 by the spring 45. Water will then flow from the chamber 20 through the nipple 33, through the valve 6, and out the conduit 51. Whenever the pressure in the discharge chamber 20 drops below the predetermined amount, it will no longer be able to overcome the force exerted on the valve member 43 by the spring 45, and the spring 45 will therefore force the valve member 43 inwardly against the seats 37 and 40 to stop the flow of water through the valve.

The operation of the pump 5 is substantially the same as that of conventional centrifugal pumps. However, by the use of the improved cover plate 21, the use of an expensive and bulky adapter has been eliminated. Upon priming the improved pump 5 (through a priming opening not shown), the entire volume of the chamber formed by the recess 13 and the cover plate 21 fills with water, there being no dome-shaped portions in the improved housing cover plate under which air can be trapped and from which said air must be vented, as is the case with adapters for conventional pumps having rotary seals.

The improved cover plate 21 permits mounting of the motor 7 directly thereagainst, as shown in Fig. 1, thereby providing a very compact unit. The improved pump and pressure regulating valve are substantially fool-proof and can be quickly and easily assembled or disassembled.

by reason of the small number of component parts therein. In addition, the substantial reduction in the number of parts in the improved pump and regulating valve greatly reduces the cost of manufacture thereof.

Various changes and modifications may be made without departing from the spirit of the invention, and all of such changes are contemplated, as will come within the scope of the claims.

What I claim is:

1. An electrically driven pump comprising: a rotary shaft; a rotary impeller having one side substantially flat and connected to said shaft, said impeller having a single water inlet, formed in its opposite side; a housing having a chamber in which said impeller rotates, said housing having a recess of a diameter greater than the diameter of the impeller communicating with and extending outwardly from said impeller chamber, and said housing having a rim portion surrounding the outer end of said recess and spaced axially from said impeller; a thin flat cover plate having one side seated on said rim and having a central opening through which the rotary shaft extends, the flat side of said impeller being spaced from said plate a distance substantially less than one-half the radius of said impeller; a driving motor for said shaft mounted directly on the other side of said thin flat cover plate; bolts projecting from said motor into said housing rim for removably connecting said motor and cover plate in assembled position; and a rotary seal on said motor shaft extending between said cover plate and the impeller.

2. An electrically driven pump comprising: a rotary shaft; a rotary impeller having one side substantially flat and connected to said shaft, said impeller having a single water inlet, formed in its opposite side; a housing having a chamber in which said impeller rotates, said housing having a recess of a diameter greater than the diameter of the impeller communicating with and extending outwardly from said impeller chamber, and said housing having a rim portion surrounding the outer end of said recess and spaced axially from said impeller; a thin flat cover plate having one side seated on said rim and having a central opening through which the rotary shaft extends, the flat side of said impeller being spaced from said plate a distance substantially less than one-half the radius of said impeller, said cover plate being formed in said side with a central recess; a single flat annular insert of rust resistant bearing metal mounted in said recess; a driving motor for said shaft mounted directly on the other side of said thin flat cover plate; bolts projecting from said motor into said housing rim for removably connecting said motor and cover plate in assembled position; and a rotary seal on said motor shaft extending between said cover plate insert and the impeller.

3. An electrically driven pump comprising: a rotary shaft; a rotary impeller having one side substantially flat and connected to said shaft, said impeller having a single water inlet, formed in its opposite side, and said impeller being formed in said flat side with a circular recess concentric with said rotary shaft; a housing having a chamber in which said impeller rotates, said housing having a recess of a diameter greater than the diameter of the impeller communicating with and extending outwardly from said impeller chamber, and said housing having a rim portion surrounding the outer end of said recess

and spaced axially from said impeller; a thin flat cover plate having one side seated on said rim and having a central opening through which the rotary shaft extends, the flat side of said impeller being spaced from said plate a distance substantially less than one-half the radius of said impeller; a driving motor for said shaft mounted directly on the other side of said thin flat cover plate; bolts projecting from said motor into said housing rim for removably connecting said motor and cover plate in assembled position; and a rotary seal on said motor shaft having one end seated in said recess, said seal extending between said impeller and said cover plate.
